Primary Examiner — George D. Kirschbaum*Assistant Examiner* — Lillian Windham*(74) Attorney, Agent, or Firm* — Lee & Hayes, P.C.**CLAIM**

The ornamental design for a video doorbell, as shown and described.

DESCRIPTION

FIG. 1 is a top, front, right-side perspective view of a video doorbell;

FIG. 2 is a bottom, back, left-side perspective view thereof;

FIG. 3 is a front view thereof;

FIG. 4 is a back view thereof;

FIG. 5 is a left-side view thereof;

FIG. 6 is a right-side view thereof;

FIG. 7 is a top view thereof; and,

FIG. 8 is a bottom view thereof.

The dashed broken lines depict portions of the video doorbell that form no part of the claimed design.

1 Claim, 8 Drawing Sheets(56)
